W. Clemson,

Cross Cut Saw Handle.

No. 91,716.

Patented June 22, 1869.

By A. Crawford atty.

United States Patent Office.

WILLIAM CLEMSON, OF MIDDLETOWN, NEW YORK.

Letters Patent No. 91,716, dated June 22, 1869.

IMPROVEMENT IN HANDLES FOR CROSCUT-SAWS.

The Schedule referred to in these Letters Patent and making part of the same.

To all whom it may concern:

Be it known that I, WILLIAM CLEMSON, of Middletown, in the county of Orange, in the State of New York, have invented a new and improved Mode of Attaching Handles to Croscut-Saws; and I do hereby declare that the following is a full and exact description thereof, reference being had to the accompanying drawings, and to the letters of reference marked thereon.

My invention consists of the combination of the devices used by which the handle is firmly attached to the saw.

To enable others skilled in the art to make and use my invention, I will describe its construction and operation.

In the drawings—

Figure 1 represents a section of a saw with the handle attached;

Figure 2 is a cross-section of same;

Figure 3 is a view of the upper end of the ferrule on the handle; and

Figure 4 is a section of the inclined slotted clamp-block.

A represents a part of the blade of a common cross-cut-saw.

E is a looped or slotted screw-shank, having the saw A inserted in the slot.

D is an inclined slotted clamp-block, having a hole in its centre, through which shank E freely passes, and is made higher on one side than on the other, to fit the taper of the saw, and has a concave slot, a, on its inclined end, which fits closely upon the back of the saw.

C is a ferrule, with a solid end, c, in which is a female screw, and into which the screw on the end of the shank enters.

This ferrule has ribs d, more or less in number, on its inside, that fit into grooves cut into the wood of handle B, that is enclosed by such ferrule.

B is a common wood handle, with the ferrule above described firmly fixed upon it, and has a hole in the centre of its lower end to receive the screw on the end of shank E.

The slot a in clamp-block D is made concave, to insure a close fit on the back of the saw, at its outer contact with the saw, as seen in red lines, as seen in dotted lines, in fig. 1

The ribs d, on the inside of the ferrule, prevent the handle from turning in, and without turning the nut e on the screw-shank.

When the ferrule C is placed on the handle B, the screw-shank is passed through clamp-block D, and is then screwed into the nut-part of the ferrule C, the clamp-block D turned so that the inclined side fits the taper of the back of the saw, which is inserted in the loop-part of the shank, and the slot in the block embraces the back of the saw, as seen in fig. 1, and the handle B is turned down upon the screw-shank E, the block is forced upon the saw, and the handle is firmly fixed to the saw; and by only turning the handle in the opposite direction, the handle is released, and can be taken from the saw.

This construction and arrangement of devices make an attachment that is cheap, easily operated, and that can be depended upon for security, as well as durability, and not likely to get out of order, and admits of a considerable variation of width in saw-blades, and allows the handle to always be at right angles with the saw.

I am aware that slotted screw-shanks, inserted in handles, have been used for attaching handles to saws; such slotted screw-shanks or hooks I do not claim. Nor do I claim for the ribs on the inside of the ferrule, as such ribs are old and in use; but having described my invention,

What I claim, and desire to secure by Letters Patent, is—

The combination of the slotted screw-shank E, inclined slotted block D, ferrule C, and handle B, when constructed and arranged to operate together, in the manner and for the purpose described.

WM. CLEMSON.
